[57] CLAIM

The ornamental design for a writing instrument, as shown and described.

DESCRIPTION

FIG. 1 is a top plan view of a writing instrument showing my new design;
FIG. 2 is an enlarged scale left end elevational view;
FIG. 3 is an enlarged scale right end elevational view;
FIG. 4 is a front elevational view of FIG. 1, the opposite side being a mirror image thereof; and
FIG. 5 is a bottom plan view thereof.

Fig. 1.Fig. 2.Fig. 3.Fig. 4.Fig. 5.
